UNITED STATES PATENT OFFICE.

STANLEY J. SHEPARD, OF PASADENA, CALIFORNIA.

DESIGN FOR A SIGN NOVELTY.

Application filed October 20, 1928. Serial No. 28,577. Term of patent 3½ years.

To all whom it may concern:

Be it known that I, STANLEY J. SHEPARD, a citizen of the United States, and resident of Pasadena, in the county of Los Angeles and State of California, have invented a new, original, and ornamental Design for Sign Novelty, of which the following is a specification, reference being had to the accompanying drawing, forming part thereof.

Figures 1, 2, and 3 are front, rear, and edge views, respectively, of a sign novelty, showing my new design.

I claim:

The ornamental design for a sign novelty, as shown.

STANLEY J. SHEPARD.
